Primary Examiner — Nicole C Shiflet

Assistant Examiner — Danielle Nichole Bowly

(57) **CLAIM**

The ornamental design for a printing machine, as shown and described.

DESCRIPTION

1. Printing machine
2. Printing machine
- 1.1 : Front
- 1.2 : Back
- 1.3 : Top
- 1.4 : Bottom
- 1.5 : Left
- 1.6 : Right
- 1.7 : Perspective
- 2.1 : Front
- 2.2 : Back
- 2.3 : Top
- 2.4 : Bottom
- 2.5 : Left
- 2.6 : Right
- 2.7 : Perspective

(Continued)

The broken lines in the drawings illustrate portions of the printing machine which form no part of the claimed designs; the solid black surface shading is used to represent the color black.

1 Claim, 14 Drawing Sheets
